UNITED STATES PATENT OFFICE.

HENRY TRUESDELL, OF TORONTO, CANADA, ASSIGNOR TO THE CYCLONE
GRATE BAR COMPANY, LIMITED, OF SAME PLACE.

FURNACE-GRATE.

SPECIFICATION forming part of Letters Patent No. 655,663, dated August 7, 1900.

Application filed April 8, 1899. Serial No. 712,344. (No model.)

To all whom it may concern:

Be it known that I, HENRY TRUESDELL, of the city of Toronto, in the county of York and Province of Ontario, Canada, have invented 5 certain new and useful Improvements in Furnace-Grates; and I hereby declare that the following is a full, clear, and exact description of the same.

This invention relates to a furnace-grate in 10 which will be combined durability, economy of fuel, and simplicity of operation.

Unless a practically-perfect combustion takes place within the furnace a consequent loss of fuel is the result, with a corresponding 15 loss of heat. To obtain this perfect combustion, it is necessary to so arrange the grate-bars that they can be kept thoroughly clean—that is to say, free from ashes and clinkers—and to so arrange them that air currents or 20 drafts can have free access to the fire.

To so construct a furnace-grate that a practically-perfect combustion can be obtained and to so arrange the grate-bars that they can be cheaply and economically made and re- 25 paired and simply operated is the object of the present invention, which consists of a furnace-grate embracing in its construction a plurality of independent grate-bars, each consisting of a substantially-rectangular 30 frame, a plurality of independent sections removably mounted on the sides of the frame, which are trussed to allow of the free circulation of the air-currents and to withstand the ordinary strains to which the grate-bar is 35 subjected, and a gudgeon for each end of the grate-bar, so formed that it will revolvably and removably interlock with the bearings of the journal-plates, the end of each grate-bar being connected to an operating bar or rod 40 moved by a lever to rock the grate-bars to disintegrate the coal in the furnace and free the furnace from ashes or to place the grate-bars in such a position that the contents of the furnace can be dumped into the ash-pit, 45 as hereinafter more fully set forth, and more particularly pointed out in the claims.

In the drawings, Figure 1 is a perspective view of a portion of the furnace of a boiler,

showing the relative position of the several parts of the furnace-grate. Fig. 2 is a perspective view of one of the grate-bars. Fig. 3 is a perspective view of the frame of the grate-bar. Fig. 4 is a perspective view of one of the removable sections of the grate-bar. Fig. 5 is a perspective view of one of the journal-plates. Fig. 6 is a perspective view from the inner side of the front support and journal-plates. Fig. 7 is a side elevation showing the mechanism for rocking the grate-bars.

Like letters of reference refer to like parts throughout the specification and drawings.

A represent the grate-bars, each of which consists of a substantially-rectangular frame A', a plurality of independent sections A'', removably mounted on the sides of the frame 65 A', and gudgeons A³, integrally formed with the middle of the ends of the frame A'. The frame A' consists of two opposite sides a a and ends a' a', integrally formed with the ends of the sides a a. The lower edge of each 70 of the sides a a is arched to form a truss a'' to enable the sides to support the weight of the grate-bar and the weight of its proportionate share of the contents of the furnace without bending. Each of the ends a' a' projects beyond the outer faces of the sides a a 75 to form the end sections of the grate-bars, and the lower edge of each of the ends a' a' is arched to form a convexed truss, while the top a³ of each of the ends a' a' is convexed 80 and is provided with lateral corrugations B to allow of the air-currents passing longitudinally along the grate-bar and with longitudinal corrugations C to allow of the air-currents passing laterally across the grate- 85 bar. Each of the sections A'' is equal in length to the length of the ends a' a', and the top of each of the sections A'' is convexed or arched to correspond to the arch of the top 90 of the ends a' a' and is provided with lateral corrugations B and longitudinal corrugations C, corresponding to the corrugations of the ends a' a'. Projecting inwardly from the lower edge of each of the sections A'' are two notches D, equal in width to the thickness of 95 the sides a a and arranged equidistant from

each end of the section. The distance between the notches D is equal to the width of the frame A' in order that when the sections A'' are being assembled in place the top of 5 the sides a a will enter the notches D. The top of each of the sides a a is provided with a series of notches D', arranged equidistant from each other and from the ends a' a'. The notches D' correspond in width to the thickness 10 of the sections A'' and receive the sections when they are assembled in position, the sides of the notches D' embracing the sides of the sections A'', while the sides of the notches D embrace the inner and outer faces 15 of the sides a a of the frame, thus enabling the sections A'' to be removably locked in position on the sides a a. The notches D D' are of such a depth that when the sections are locked in position the top of the sections 20 will be approximately in the same plane as the top of the sides a a. That part of the sides a a between each adjacent pair of sections A'' is concaved to admit of the air-currents passing into the furnace between the 25 sides of the sections. The lower edge of each of the sections A'' between the notches D is concaved to provide a passage for the air-currents below the grate-bar and also to assist the sections in resisting compression.

30 By trussing the sides and ends of the frame and the sections the compression of the various parts by the weight upon them is resisted. Consequently a greater strength is obtained from the same quantity of metal for a grate-bar of this construction than if the parts were 35 not trussed.

By making the sections removable and locking them in position in the manner above described it is possible in the case of injury 40 to one or more of the sections to remove the injured section or sections and replace it or them with new ones without disturbing any of the remaining sections or parts of the grate-bar, thus effecting a large saving in the 45 cost of repairs. Again, by providing the under side of each of the sections with a concaved arch and corrugating the tops of the sections and ends of the frame laterally and longitudinally and concaving the sides of the 50 frame between the sections it is possible to provide the furnace with a considerable volume of air to aid the combustion taking place within it, at the same time preventing the adherence of clinkers to the grate-bar.

55 It will be noticed by reference to the drawings that the top e of each of the gudgeons A³ is flattened.

F F represent the journal-plates, each of which is provided with a series of bearings f, 60 the lower part of each of which is rounded to correspond to the rounded portion of the gudgeons A³ in order that the gudgeons can rock easily in either direction when mounted therein. Each journal-plate is provided with 65 a series of slots f', extending inwardly from

the top to the bearings f. The width of each slot is slightly less than the diameter of its respective gudgeon A³ in order that when the grate-bars are being mounted in the journal-plates it will be necessary to turn them edge-wise into the position shown in dotted lines 70 in Fig. 5 of the drawings, so that the gudgeons can move easily through the slots f' and enter the bearings f, the grate-bars then being turned into their proper position. By 75 means of this construction the gudgeons of the grate-bars are removably locked in the bearings of the journal-plates.

Each of the journal-plates F is trussed, as 80 shown in Fig. 5 of the drawings, to enable it to withstand the strains placed upon it. The front end of the journal-plate is provided with a dovetail f'', which interlocks with a corresponding dovetailed groove f³, formed in the inner face of the front support G, and are 85 supported upon an inwardly-projecting lug f⁴ at the bottom of the support G. By means of the dovetails f'' and grooves f³ the journal-plates are securely held in position.

Each of the journal-plates F intermediate 90 the bearings f is provided with grooves or nicks g, having V-shaped tops to prevent the lodgment thereon of ashes and cinders and to allow of the circulation of the air-currents over the journal-plates to the fire.

95 The front support G, it will be noticed by reference to the drawings, is trussed in a similar manner to the journal-plates F and for the same purpose.

Connected to the lower part of the ends a' 100 of the grate-bars is a shaking-rod H, which projects through the front I of the boiler-casing, and connected to the front end of the rod H is a lever J, by means of which it is operated to rock the grate-bars in either direction. When it is necessary to clean the fire—that is, to remove the ashes and cinders—the lever is limited to a slight reciprocating movement to rock the grate-bars sufficiently to agitate the contents of the furnace, and when it is necessary to dump the 105 contents of the furnace into the ash-pit the lever is moved to its fullest extent to upset the grate-bars and allow of the fire falling through them.

110 By constructing the grate-bars on the above principle the furnace is provided with a sufficient air current or draft to insure a practically - complete combustion, while at the same time the furnace is strongly and cheaply 115 constructed and thoroughly durable.

Having thus fully described my invention, what I claim as new, and desire to secure by Letters Patent, is—

1. A grate-bar comprising a rectangular 125 frame having tapering slots in its sides, a number of wedge-shaped cross-bars fitting within the tapering slots and provided with parallel slots on their lower edges engaging the frame below the tapering slots, said cross-bars be- 130

ing provided with corrugated top surfaces, and suitable gudgeons formed on the ends of the frame substantially as described.

2. A grate-bar comprising two plates with 5 tapering slots therein, a number of wedge-shaped cross-bars fitting within the tapering slots and provided with parallel slots on their

lower edges engaging the plates below the tapering slots, substantially as described.

Toronto, Canada, December 14, A. D. 1898.

HENRY TRUESDELL.

In presence of—

M. A. WESTWOOD,
C. H. RICHES.
